LEVELING INSTRUMENT

William L. Heffern, St. Petersburg, Fla.

Application April 9, 1951, Serial No. 14,763

Term of patent 14 years

(Cl. D52—1)

To all whom it may concern:

Be it known that I, William L. Heffern, a citizen of the United States of America and a resident of the city of St. Petersburg, State of Florida, have invented a new, original, and ornamental Design for Leveling Instrument, of which the following is a specification, reference being had to the accompanying drawing, forming part thereof, wherein:

Fig. 1 is a top plan view of a leveling instrument, showing my new design;

Fig. 2 is a side elevational view thereof;

Fig. 3 is a bottom view thereof; and

Fig. 4 is an end view thereof.

The characteristic features of the design reside in the portions shown in solid lines.

I claim:

The ornamental design for a leveling instrument, as shown and described.

WILLIAM L. HEFFERN.
